UNITED STATES PATENT OFFICE.

SAMUEL J. SHIMER, OF MILTON, PENNSYLVANIA.

KNIFE FOR WOOD-WORKING MACHINES.

SPECIFICATION forming part of Letters Patent No. 296,077, dated April 1, 1884.

Application filed February 2, 1884. (No model.)

To all whom it may concern:

Be it known that I, SAMUEL J. SHIMER, a citizen of the United States of America, a resident of Milton, in the county of Northumberland, in the State of Pennsylvania, have invented a new and useful Knife or Cutter for Wood-Working Machines, of which the following is a specification.

My invention relates to certain new and useful improvements in "knives" or "cutters" for wood-working machines, especially those knives or cutters intended to be secured to a rotary cutter-head.

Previous to my invention it has been found that the cutter-heads of wood-working machines often present a rough face where the knives are secured, owing to the cutting-edges of said knives being in line with their under faces, and thus forcing the chips and splinters raised by the cut against and in between the cutters and their heads. The bolts employed to secure the knives to said heads are also subjected to a great amount of strain on account of such wedging, thereby requiring frequent oversight and adjustment of the cutting apparatus in order to secure uniform finish of the work.

The object of the present invention is to provide a simple and economical cutter or knife for wood-working machines that will present a perfect chip-break adapted to wear into shape, and thus automatically adjust itself to the cut without the necessity of special attention or adjustment during the operation of the machine, and at the same time prevent the chips or splinters wedging between the knives or cutters and the heads to which they may be secured.

A further object of the invention is to secure a smooth cut over cross-grained or knotty lumber, as by the peculiar construction of the knife or cutter the chip-break causes the chip to roll or curl close to the cutting-edge and prevents a split with the grain of the wood. This peculiar construction of the knife or cutter also prevents unnecessary strain upon the bolts securing it to the cutter-head.

I accomplish these objects by rigidly uniting or affixing to the face of the tool or cutter, next to the cutting-edge thereof, a facing or layer of soft metal. The metal of this facing should be of such a nature as to readily wear away

by contact with the chips or shavings, in order that the chip-break may be formed between the steel of the cutter and the face of the cutter-head without strain on the parts.

The invention therefore consists in forming the steel knives or cutters ordinarily employed in wood-working machines with a coating or face of soft metal, as will be hereinafter more fully described with reference to the accompanying drawings, in which—

Figure 1 represents a cross-section of a rotary cutter-head, showing the application of my invention; Fig. 2, a detail perspective view of a planer-knife constructed in accordance with my invention; Fig. 3, a longitudinal vertical section on line $x-x$, Fig. 2; and Fig. 4 is a transverse sectional view of the knife.

A represents a planer-knife of the ordinary construction brought to a cutting-edge, as shown at a , and to the side next the cutting-edge is soldered or otherwise rigidly secured a layer of soft metal, forming a coating or face, B, the thickness of this layer being varied at pleasure, in order to carry out the above-enumerated objects of the invention in the best possible manner. The knife A, with its soft-metal coating or face B, is secured to the cutter-head C on the line $b-c$ by means of bolts D, such means being that usually employed for that purpose. It will be readily seen that the cutting-edge a is not on a line with the under face of the knife, and therefore the chips or splinters raised by the cut cannot wedge themselves in between the head and cutter, while the soft-metal coating or face, standing up sufficiently close to this edge, forms a perfect chip-break, and will wear back far enough and fast enough to give the knife at all times a clear and equal cut. The chip-break formed by the soft-metal coating or face to the knife, gradually wearing into shape, needs no special adjustment or attention, and the cutting-edge, backed by this soft-metal chip-break, rolls or curls the chips up close thereto, and prevents a split after the grain when working cross-grained or knotty lumber, thereby insuring a smooth cut. The soft-metal coating or face also forms a yielding and frictional medium, and consequently the bolts holding the knife to the cutter-head are subjected to less strain than is usually the case.

This improvement applies to all sizes and

kinds of knives used in wood-working machinery, and especially to those adapted to be secured to a rotary cutter-head in the manner herein described.

5 What I claim as my invention, and desire to secure by Letters Patent, is—

1. A knife or cutter for wood-working machines, consisting of a steel body having rigidly secured to one of its faces a coating of soft metal, substantially as and for the purpose set forth.

2. A knife or cutter for wood-working ma-

chines, consisting of a steel body having soldered or otherwise rigidly secured thereto a thin layer or coating of soft metal, substantially as and for the purpose set forth. 15

In testimony whereof I have hereunto set my hand in the presence of two attesting witnesses.

SAMUEL J. SHIMER.
